UNITED STATES PATENT OFFICE.

ORR C. TRASK, OF TORONTO, ONTARIO, CANADA.

BURNER-TEMPERATURE-INDICATING MECHANISM.

Application filed April 20, 1923. Serial No. 633,566.

To all whom it may concern:

Be it known that I, ORR C. TRASK, a citizen of the United States, residing at Toronto, Ontario, Canada, have invented a new 5 and useful Improvement in Burner-Temperature-Indicating Mechanism, of which the following is a specification, reference being had therein to the accompanying drawings.

In the construction of apparatus designed 10 for the propulsion of automobiles by steam, it is the practice to provide a boiler which is supplied with water and to also provide means for heating the water in the boiler in order to produce the steam 15 for the running of the vehicle.

This heating device usually consists of a main burner and a pilot burner whose respective duties are the generating of steam for the running of the vehicle and the maintenance of sufficient steam so that when the 20 vehicle is left standing for a period, it is possible to again operate the same without great delay in raising steam.

These pilot burners usually consist of a 25 tubular member having slots therein and a feed pipe which feeds vaporized fuel therein.

In the operation of steam automobiles, I have found that the pilot burner flame 30 oftentimes dies out without the knowledge of the driver, with the result that the vaporized fuel is fed therein and does not burn with the consequent result that the water in the boiler is allowed to cool. This escape 35 fuel is likewise a dangerous element from an explosive standpoint.

It is the prime object of my invention to overcome this difficulty by providing means for indicating such condition to the driver 40 of the vehicle immediately upon its happening.

Another object of my invention is to provide such a mechanism of simple and compact structure and one easy of manufacture 45 and assembly.

With these and other objects in view, my invention consists in the arrangement, combination and construction of the various parts of my improved device as described 50 in the specification, claimed in my claim and shown in the accompanying drawings, in which:

Fig. 1 is a view looking upwardly from the ground at a steam boiler with a pilot

burner attached thereto and showing an indicating machine in operable connection therewith.

Fig. 2 is a plan view of a pilot burner showing an indicating mechanism attached thereto and

Fig. 3 is a sectional view taken on line 3-3 of Fig. 2.

I have shown a conventional steam boiler 1 having disposed therein conventional tubes 2 and provided with the usual pilot burner 3.

In the practical operation of my improved device, fuel is carried from a source of supply through the tube 4 which is bent at 5 so as to form a V shaped member 6 and thence through the tube 6 into the pilot 70 burner 3 where it is ignited. The tube 4 passes over the pilot burner 3 as shown in the drawings so that the fuel will be pre-heated and better vaporized before entering the burner.

I attach to the side of the pilot burner 3 by a suitable means (shown here as a band 7 attached to the pilot burner 3 by means of rivets 8 and welds 9), a tube 10 which may be filled with toluol or any other temperature indicating matter which tube 10 is connected through the tubing 11 with an indicating device 12.

In the drawings I have shown this indicating device in diagrammatic relation to the operating parts hereinbefore described but in the practical operation of my improved mechanism, it would preferably be located upon the dash of the automobile.

The indicating mechanism 12 is so connected with the toluol or similar matter in the tube 10 that it will register in accordance with the temperature surrounding the said tube 10 with the consequent result that when the said pilot burner 3 is burning normally, the indicating finger 13 on the indicator 12 will so indicate and when the pilot burner 3 is not burning, the indicating finger 13 will be lowered to the off position because of the drop in temperature of the atmosphere coming from the burner 3 to the tube 10, thus notifying the operator of the vehicle that the pilot burner 3 is not operating.

It is obvious that some changes will be made in the arrangement and combination of the various parts of my improved device without departing from the spirit of

the invention therein and I do not wish to limit myself to the exact structure shown, it being my intention to cover by my claim such changes as may be reasonably included within the scope thereof.

What I claim is:

In combination, a burner having a tubular member adjacent thereto, said tubular mem-

ber containing temperature sensitive matter, an indicator connected with said member so that variations of temperature around the said burner will be transmitted through the tubular member and the temperature sensitive matter to the indicator.

ORR C. TRASK.
